(57) CLAIM

The ornamental design for a bed blanket, as shown and described.

DESCRIPTION

The file of this patent contains at least one drawing executed in color. Copies of this patent with color drawings will be provided by the Patent and Trademark Office in view of the Petition and requisite fee submitted herewith.

FIG. 1 is a front elevational view of a bed blanket, with the rear elevational view being a mirror image thereof,

FIG. 2 is a side elevational view taken from the left side of FIG. 1, with the right side elevational view being identical thereto,

FIG. 3 is a top plan view thereof, with the bottom plan view being identical thereto; and,

FIG. 4 is a perspective view thereof.
